FULL-FLOATING HOLDER

Milton L. Benjamin, Shaker Heights, and Franklyn E. Winnen, Cleveland, Ohio; said Winnen assignor to said Benjamin

Application November 30, 1949, Serial No. 130,262

12 Claims. (Cl. 279—16)

1

The present invention relates generally as indicated to a full floating holder and has for one of its main objects the provision of a holder which utilizes an entirely new principle to compensate for both angular and parallel misalignment between the tool and the work spindles of machine tools, for example.

It is another object of this invention to provide a full floating holder in which the pressure required to hold the parts in adjusted position is applied through an elastic support sleeve made of rubber or rubber-like material.

Another object is to provide a holder of the character indicated in which accurate alignment between a tool adapted to be held in the holder and a workpiece to be operated upon by said tool and carried by the work spindle can be effected in a most efficient manner to increase production and to reduce scrap and tool cost and wear to a minimum.

Other objects and advantages will become apparent as the following description proceeds.

To the accomplishment of the foregoing and related ends, said invention, then, comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is an exploded view of a collet type holder, some of the parts being shown wholly or partly in cross-section;

Fig. 2 is a cross-section view on an enlarged scale of the parts in Fig. 1 in assembled relation;

Fig. 3 is a cross-section view of a floating holder shank of the straight bushing type as distinguished from the collet type illustrated in Figs. 1 and 2;

Fig. 4 is a cross-section view of a floating holder shank of the taper shank type; and

Figs. 5 and 6 are cross-section views of modified support sleeves.

Referring now more specifically to the drawing and first more particularly to Fig. 1, the first part at the left-hand side is the main shank or housing 1 which is provided with an elongated shank portion 2 adapted to be secured to the tool spindle of a metal working machine. Said housing 1 is further provided with an enlarged tubular exteriorly threaded portion 3 within which is formed a conical seat 4. At diametrically opposite sides of said seat and extending axially

beyond the base of said seat 4 are a pair of cylindrical pins 5 press-fitted into said housing. Said pins 5 are also disposed within the enlarged portion 3 of said housing.

Next is a series of three members 6, 10, and 15 insertable into housing 1 and respectively having a universally tiltable and driving connection with said housing and transversely movable and driving connections with each other along angularly disposed paths.

The first of said series of members is a drive plate or ring 6 which is formed with a spherical protuberance 7 adapted to engage in line contact with the conical seat 4 and formed with a radially extending flange 8. Said flange 8 is formed with four equally spaced peripheral notches 9, two of which notches are adapted to loosely fit over the projecting ends of the pins 5 to enable driving engagement between housing 1 and said ring 6 and universal tilting of said ring while in engagement with seat 4.

The second or intermediate one of said series of members 6, 10, and 15 is a ball retainer ring 10 carrying a plurality of circularly arranged balls 11 therein each of diameter slightly greater than the thickness of said ring 10 and extending beyond opposite faces of said ring. The balls 11 are held in place so as to lie in a common plane and so to be rotatable in said ring as by peening over the opposite faces of said ring 10.

Said retainer ring 10 is formed with diametrically opposed and axially extending lugs 12 adapted to loosely fit within the other pair of notches 9 in said drive ring 6 to enable driving of said ball retainer ring 10 through said drive ring and adjustment of the latter along a path transverse to its axis. Said ring 10 is further formed with another pair of similar diametrically opposed lugs 14 which extend axially in the opposite direction and 90° out of phase with the lugs 12, as shown.

The third or last one of said series of members 6, 10, and 15 is a floating holder shank 15 of tubular form threaded at one end as shown and formed with a flange 16 at the other end, such flange being formed with a pair of diametrically opposed notches 17 adapted to loosely fit over lugs 14 of said ball retainer ring 10 whereby said holder shank 15 may also be adjusted transversely of its axis but along a path at right angles to the path of transverse adjustment of the ball retainer ring 10. The fit of the notches 17 over the lugs 14 in addition provides a driving connection with ball retainer ring 10.

Said holder shank 15 is provided with a bore

containing coaxial and axially spaced conical seats 18 and 19 comparable with the seats formed in the shank member disclosed for example in the Milton L. Benjamin et al. Patent No. 2,358,300 which issued on September 19, 1944.

Next after said series of members is a spacer ring 20 and a support sleeve 21 both having a loose fit over the threaded portion of the holder shank 15, said spacer ring 20 being disposed to engage the side of the flange 17 which is opposite to said ball retainer ring 10. Said support sleeve 21 is of rubber or rubber-like material and, as will hereinafter appear, pressure is adapted to be applied through said sleeve to clamp the drive ring 6, the ball retainer ring 10, and the holder shank 15 in desired tilted and transverse adjusted positions within said housing 1.

Next in Fig. 1 is a contractible collet 22 of a form such as that disclosed in the aforesaid Benjamin et al. patent provided with conical faces 23 and 24 engageable with the conical seats 18 and 19 respectively in said holder shank 15. As apparent, endwise movement of said collet 22 into said holder shank 15 will effect contraction of said collet so as to grip a tool or the like therein.

Next, is an internally threaded adjusting nut 25 which is adapted to be threaded into the portion 3 of housing 1, said nut being formed with an inturned flange 26 having a loose fit over the threaded portion of holder shank 15. As apparent, tightening of said nut 25 onto housing 1 will effect clamping of the previously described series of members 6, 10, and 15 in a desired adjusted position by pressure applied through the elastic support sleeve 21.

Next, is a nose ring 27 and a nose-piece 28, the latter being threadably engageable with the holder shank 15 whereby the nose ring 27 will engage the outer end of collet 22 to effect the desired endwise movement and contraction of said collet to grip a tool therein.

The afore-described parts are shown in assembled position in Fig. 2 with a reamer R gripped in collet 22. For sake of illustration, housing 1 in Fig. 2 is shown in both angular and parallel misalignment with a work spindle 29, the axes of said housing 1 and said spindle 29 being represented by the lines 30 and 31 respectively and the axis of said drive ring 6 being represented by the line 32 to show the angular and parallel misalignment.

With the adjusting nut 25 tightened by hand or with light wrench pressure, the tool R may readily be shifted angularly and transversely to bring its axis into perfect alignment with the axis 31 of the work spindle 29, as shown, such shifting being made possible by the drive ring 6 being universally tilttable when in engagement with conical seat 4 in housing 1 and by the ball retainer ring 10 and the holder shank 15 being transversely movable with respect to their axes along angularly disposed paths. In this partly assembled position the balls 11 are engaged between the flanges 8 and 16 of said drive ring 6 and said holder shank 15 to facilitate transverse movement of the retainer ring and holder shank and to function more or less as a thrust bearing.

With the tool R in proper alignment as aforesaid, nut 25 may then be tightened to fix the tool R in such properly adjusted position.

The tightening of nut 25 as aforesaid exerts pressure on elastic support sleeve 21 which

through the pressure thus applied on spacer ring 20, flange 16 of holder shank 15, and balls 11 of ball retainer ring 10 on said drive ring 6 effects firm seating in line contact of spherical surface 1 with cone seat 4.

Although the pressure around support sleeve 21 may vary somewhat due to the angular misalignment, but, for the most part, the pressure is more or less equalized or balanced due to the behavior of the rubber or rubber-like material from which said support sleeve is made in a manner similar to pressure applied upon a confined fluid. In this way, the frictional resistance to movement of the drive ring 6 relative to housing 1 is greater than the tendency of said support sleeve to return to its normal undistorted shape, this being attributed to the higher unit pressure of the line contact between said housing 1 and said drive ring 6 than that applied on said support sleeve. With regard to parallel movement, the tool R may yet resiliently partake of a limited amount of such movement as permitted by the transverse clearance between support sleeve 21 and holder shank 15.

It is to be understood that the reamer R is herein shown for illustrative purposes only and therefore other tools such as taps and the like may be similarly gripped in collet 22 as well as workpieces which it is desired to align with tools or other parts of the machine. Obviously other forms of gripping devices may be used.

For example, the holder shank may comprise a straight bushing 33 as illustrated in Fig. 3 and provided with a set screw 34 for applying gripping pressure on the shank of the tool or said holder shank may be of the taper shank type as shown in Fig. 4 comprising a shank 35 loosely extending through the bores in ball retainer ring 10 and drive ring 6 to permit desired tilting and transverse movements and provided with a tapered bore 36 adapted to receive a correspondingly tapered shank of the tool or the like. The transverse opening 37 through the shank 35 enables convenient removal of the tool by the usual wedge pin (not shown). In such case, housing 1 will also be provided with a transverse opening in register with the opening 37 aforesaid. In both of the modifications illustrated in Figs. 3 and 4 the flanges 16 thereon correspond with the flanges 16 on holder shank 15 and the diametrically opposed notches 17 correspond with like notches formed in holder shank flange 16.

In the modification illustrated in Fig. 5, two spacer rings 20 are provided, one located on each side of support sleeve 21, and as evident it may be desirable in some instances to omit both of these spacer rings whereby said support sleeve will directly engage flange 16 of holder shanks 15, 33 or 35 as the case may be.

In the modification illustrated in Fig. 6 spacers 38 are provided with axial flanges 39 to restrict distortion of support sleeve 40 therebetween and therearound only in a radially outward direction 65 so as to always assure a transverse clearance with holder shanks 15, 33, or 35. Here again, one or both of the spacers 38 may be omitted and if only one is provided, the axial flange 39 thereof may be correspondingly longer.

In any event, the support sleeve 40 is arranged to have axial pressure applied thereon between the inturned flange 26 of adjusting nut 25 and flange 16 of holder shank 15, 33, or 35 whereby such pressure in turn is transmitted through the 75 remaining parts 11 and 6 to effect tight engage-

ment of drive ring 6 with conical seat 4 in substantially line contact.

It should be borne in mind that conical seat 4 and spherical protuberance 7 may be reversed, that is, the spherical surface may be in the form of a protuberance in housing 1 and the conical surface may be in the nature of a flare mouth in drive ring 6, thus yet permitting the universal tilting of said drive ring with respect to housing 1. Likewise seat 4 may be of spherical form with said drive ring 6 terminating in a sharp edge engaging such seat in line contact and permitting universal tilting of said drive ring. Moreover, various modifications, too numerous to mention, may be made in the cavity in which the support sleeves 21 or 40 and spacers 21 or 38 are disposed just so long as pressure applied on said support sleeves in turn exerts pressure to hold the drive ring 6 in a desired adjusted tilted position and to frictionally clamp the holder shank 15, 33, or 35 and ball retainer ring 10 in desired adjusted transverse positions to cure both angular and parallel misalignment between housing 1 and work spindle 29 or the like.

Other modes of applying the principle of the invention may be employed, change being made as regards the details described, provided the features stated in any of the following claims, or the equivalent of such, be employed.

We therefore particularly point out and distinctly claim as our invention:

1. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing.

2. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, said housing and the first of said series of members being formed with interengaged conical and spherical seats forming such universally tiltable connection.

3. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, said housing and the first of said series of members being formed with interengaged conical and spherical seats forming such universally

tiltable connection, such seats being engaged substantially in line contact whereby to effectively retain said first member in adjusted position upon clamping thereof through said elastic member as aforesaid.

4. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, an intermediate one of said series of members carrying a plurality of balls respectively engaged with the members on opposite sides whereby to facilitate transverse adjustments.

5. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of member in adjusted tilted and transverse positions with respect to said housing, the last of said series of members including means for gripping a tool or the like whereby by tilting and transversely adjusting said series of members the tool may be positioned with its axis in a predetermined relation to said housing.

6. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, the driving connection between the first of said series of members and said housing comprising loosely interfitting projections and notches which enable relative tilting movement of said housing and said first member.

7. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, the transversely movable and driving connections of said series of members with each other comprising loosely interfitting portions between the first and second of

said members and between the second and third of said members.

8. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, the last of said series of members extending through said elastic member and having transverse clearance therewith.

9. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, and a spacer member between said elastic member and the last of said series of members.

10. In a floating holder for tools and the like, the combination of a housing, a series of at least three members respectively having a universally tiltable and driving connection with said housing and having transversely movable and driving connections with each other along angularly disposed paths, an elastic member adjacent the last of said series of members, and a clamping nut movable with respect to said housing for applying pressure on said elastic member and thus resiliently clamp said series of members in adjusted tilted and transverse positions with respect to said housing, the last of said series of members extending through said elastic member and having transverse clearance therewith, and a spacer member including an axial flange within said elastic member to preclude closing of such transverse clearance upon application of pressure to the latter by said clamping nut.

11. In a floating holder for tools and the like, the combination of a housing, a tool gripping assembly having a universally tiltable and transversely movable positive driving connection with said housing, a clamping nut having threaded engagement with said housing, and an elastic member engaged between said nut and assembly for resiliently clamping said assembly in adjusted tilted and transverse position with respect to said housing.

12. In a floating holder for tools and the like, the combination of a housing, a tool gripping assembly having a universally tiltable and transversely movable positive driving connection with said housing, a clamping nut having threaded engagement with said housing, and an elastic member engaged between said nut and assembly for resiliently clamping said assembly in adjusted tilted and transverse position with respect to said housing, said tool gripping assembly comprising a series of at least three members, one of which has a universally tiltable and positive driving connection with said housing, another of which has a transversely movable and positive driving connection with said one member, and still another one of which is adapted to grip a tool therein and has a transversely movable and positive driving connection with said another member along a path angularly disposed with respect to the path of transverse movement between said one and another members.
